DESIGN FOR A COMBINED POCKETBOOK AND SHOPPING BAG

Edmond Foret, New York, N. Y., assignor to Cartier, Inc., New York, N. Y., a corporation of New York

Application June 25, 1943, Serial No. 110,525

Term of patent 7 years

To all whom it may concern:

Be it known that I, Edmond Foret, a generally licensed French national and French citizen, having first papers for citizenship of the United States, residing at New York city, in the county and State of New York, have invented a new, original, and ornamental Design for a Combined Pocketbook and Shopping Bag, of which the following is a specification, reference being had to the accompanying drawing, forming part thereof.

In the drawing:

Fig. 1 is a perspective view of a combined pocketbook and shopping bag showing my new design, the shopping bag being shown in lowered, slightly opened position;

Fig. 2 is an edge elevational view of Fig. 1 with the shopping bag in fully closed position; and

Fig. 3 is a perspective view of the same with the bottom end of the shopping bag in raised position.

I claim:

The ornamental design for a shopping bag, as shown.

EDMOND FORET.
